(57) **CLAIM**

The ornamental design for an article of jewelry, as shown and described.

DESCRIPTION

FIG. 1 is a front perspective view of an article of jewelry showing our new design;

FIG. 2 is a front elevation view of the article of jewelry of FIG. 1;

FIG. 3 is a rear elevation view of the article of jewelry of FIG. 1;

FIG. 4 is a right side view of the article of jewelry of FIG. 1;

FIG. 5 is a left side view of the article of jewelry of FIG. 1;

FIG. 6 is a top side view of the article of jewelry of FIG. 1;

FIG. 7 is a bottom side view of the article of jewelry of FIG. 1;

FIG. 8 is a rear perspective view of the article of jewelry of FIG. 1;

FIG. 9 is a perspective view of the article of jewelry of FIG. 1, shown in a state of use;

FIG. 10 is another perspective view of the article of jewelry of FIG. 1, shown in a state of use; and,

FIG. 11 is another environmental perspective view of the article of jewelry of FIG. 1, shown in a state of use.

The broken lines shown in the drawings represent environmental subject matter only and form no part of the claimed design.
